UNITED STATES PATENT OFFICE

136,324

DESIGN FOR AN AGITATOR FOR MILK

Owsley E. Carman, Vale, Oreg.

Application June 12, 1943, Serial No. 110,436

Term of patent 14 years

To all whom it may concern:

Be it known that I, Owsley E. Carman, a citizen of the United States, residing at Vale, in the county of Malheur and State of Oregon, have invented a new, original, and ornamental Design for an Agitator for Milk, of which the following is a specification, reference being had to the accompanying drawing, forming part thereof.

Figure 1 is a front elevational view of an agitator for milk showing my new design,

Figure 2 is a side elevational view thereof,

Figure 3 is a top plan view, and

Figure 4 is a bottom plan view.

I claim:

The ornamental design for an agitator for milk, as shown.

OWSLEY E. CARMAN.
